UNITED STATES PATENT OFFICE.

CHARLES WILLIAM GRANT, OF LYNN, MASSACHUSETTS.

GAME.

Application filed May 11, 1926. Serial No. 108,320.

This invention relates to a game and resides more particularly in a novel form of game apparatus whereby a game simulating baseball can be played, it being possible to 5 determine the plays by the ultimate position of a ball after being projected from a position at the home plate.

A further object is to provide a means whereby a certain amount of skill on the 10 part of the player is required in order to place the ball where the most desirable results will be obtained.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed may be made within the scope of what is claimed without departing from the spirit of the invention.

In the accompanying drawings the preferred form of the invention has been shown.

25 In said drawings,

Figure 1 is a plan view of a game board constituting the present invention.

Figure 2 is a section on line 2—2, Figure 1.

30 Referring to the figures by characters of reference 1 designates the game board per se which can be made of any desired material. This board is surrounded preferably by an upstanding wall 2 of netting the upper edge of which can be reinforced with a wire 3. The netting has an opening 4 at the center of the front of the board and formed in the board 1 adjacent this opening is a recess 5. An inclined chute 6 is mounted 35 on the board and has its lower end overhanging the middle portion of the recess 5 as shown at 7. This chute is adapted to receive a ball 8 of wood or other material, and game pieces in the form of disks 8' 40 and game pieces in the form of disks 8" are also used.

Suitably outlined on the board 1 is a playing field including a diamond indicated at 9 and an outfield. The home plate is represented by a depression 10 located close to the recess 5. Arranged in the outfield portion of the board back of and at the sides of the first base, second base and third base positions are clusters of grooves or channels 11 cut into the top surface of the board. 45 These channels can be arranged in any manner desired. In the form illustrated they

are shown in groups, the channels of each group radiating from a common center and communicating with the channels of other groups. If desired, however, the channels 60 can be positioned in any other suitable way. The different channels can be provided with play designating words or characters. For example in one channel may be printed or otherwise displayed the characters 65 "B—2—1—O". This means that when a game piece is deposited in the channel so designated the play is from the batter to second base to first base where the batter 70 is out. Other designations can be arranged in other channels. For example the characters "B—1—O" meaning batter to first and out can be located near first base and at one or more places in the field can be arranged the characters "F—B—S" or 75 "F—B—O" meaning respectively, fly ball safe and fly ball out.

The various designating characters that might be used have not been indicated on 80 the drawing. Any desired plays can be designed by suitably disposed characters placed in different grooved channels. An arrow 12 is mounted to spin upon a pin 13 extending from the base 1, this arrow travelling over a circle divided into segments designated by 85 the numerals 1, 2 and 3 and by the letter H. This spinning device is employed to settle any question of doubt that might arise. For example should a player be on first base and a batter hit a fly to the outfield and be called 90 out because the game piece should stop in the recess marked "F—B—O", it would have to be determined whether the runner on first base was able to reach second base after the ball had been caught. To determine this 95 point the arrow 12 is spun and if it stops on the numeral 2 it indicates that the runner has advanced to second base on the play. If it does not stop on the numeral 2, however, the play is not made.

100 In projecting the game the ball 8 is placed at the upper end of chute 6. The ball 8 thus deposited will roll downwardly on the chute and the person playing the game places the closed hand at the opening 4 in the wall. As the ball leaves the end of the chute and drops toward the recess 5 the person playing 105 snaps with one of the fingers of the hand in an effort to hit the ball as it falls and project it to a desired position on the game board. 110 Obviously considerable skill is required in so timing the movement of the finger as to

- cause the ball to move in the direction desired. Should the person playing the game fail to hit the ball as it drops and the same remain deposited in the recess 5, the play 5 would count as a strike. Any ball landing in the spaces at the sides of the diamond in what is ordinarily foul territory will be counted as a foul ball or a strike according to the circumstances. Counters in the form 10 of balls 14 are mounted on a wire 15 supported by the board 1 and are used for keeping track of the players as they are put out. The game pieces 8' are used to indicate the 15 positions of the runners on the bases.
- Obviously various rules can be made to meet the wishes of the players and as before pointed out the various pockets or channels provided for receiving the game pieces can be suitably designated to indicate the 20 plays resulting from the landing of a game piece in any one of said channels.
- What is claimed is:
1. A game including a board, an upstanding wall therearound having an opening for receiving a finger of a player, there being a recess in the board adjacent the opening, of

laterally extending means inclined downwardly toward the opening for directing a spherical game piece to a point above and dropping it toward the recess. 30

2. A game including a board, an upstanding wall adjacent the margin thereof having an opening for receiving the finger of a player, there being a recess in the board back of said opening, a laterally extending inclined chute for feeding a spherical game piece to a point above the recess and dropping it toward the recess, there being a playing field located entirely beyond the chute and including a diamond outlined on the 35 board with a recess at the home plate positioned close to the first named recess, and a plurality of recesses in the outfield portion of the board adjacent to and beyond the diamond, any one of the recesses being designed 40 to receive the projected game piece expelled by the finger of the player from below the delivery end of the chute.

In testimony that I claim the foregoing as my own, I have hereto affixed my signature.

CHARLES WILLIAM GRANT.
